UNITED STATES PATENT OFFICE

2,510,171

FILAMENT MOUNT FOR HIGH-POWER
TUBES

John W. Clark, Cedar Rapids, Iowa, assignor to
Collins Radio Company, Cedar Rapids, Iowa,
a corporation of Iowa

Application May 25, 1948, Serial No. 28,984

13 Claims. (CL 250—27.5)

1

This invention relates to high power electron tubes, and more especially it relates to thermionic filament units or mounts for such tubes.

A principal object of the invention is to provide a more efficient thermionic filament mount for high power electron tubes.

Another object is to provide an improved multi-section filament and mount for high power tubes, wherein filament "bowing" is reduced to a minimum.

Another object is to provide a filament mount of the basket type, wherein the filament strips or sections are mounted so as to preserve their proper spaced relation with respect to an associated grid, while permitting each strip or section to elongate without "bowing."

Another object is to provide a filament mount of the basket type, wherein the effects of "end cooling" are reduced to a minimum.

A feature of the invention relates to an improved high power thermionic filament mount, wherein the filament strips are supported in parallel longitudinal array and equi-distant around a common center for cooperation with a surrounding grid.

Another feature relates to an improved high power thermionic filament mount, wherein the filament strips are supported in radial and substantially planar array with respect to a common center for cooperation with a corresponding planar grid.

Another feature relates to an improved thermionic filament and mount which is particularly useful in high power ultra-high-frequency tubes, wherein the electron transit time between the filament and control grid must be accurately determined with respect to the operating frequency of the tube. An example of such a tube is the so-called "Resnatron," as disclosed for example in U. S. Patent No. 2,405,763.

A still further feature relates to the novel organization, arrangement and relative location of parts which cooperate to provide an improved filament mount for high power electron tubes, particularly those of the ultra-high-frequency type.

Other features and advantages not particularly enumerated, will be apparent after a consideration of the following detailed descriptions and the appended claims.

In the drawing:

Fig. 1 is a generalized view, partly perspective and partly sectional, of a filament mount embodying certain features of the invention.

Fig. 2 is a vertical sectional view of one filament mount structure according to the invention.

Fig. 3 is a top plan view of Fig. 2.

Fig. 4 is a bottom plan view of Fig. 2.

Fig. 5 is a vertical sectional view of a modified filament mount according to the invention.

2 Fig. 6 is a top plan view of Fig. 5.

Fig. 7 shows the general method of supporting the mount of Figs. 2 and 3 within a tube envelope or housing.

5 Fig. 8 shows the general arrangement for supporting the filament mount of Fig. 5 within an evacuated tube or housing.

In certain kinds of high power ultra-high-frequency electron tubes, of which the so-called "Resnatron" is typical, the factor of electron 10 transit time between the cathode and control grid is of great importance. For example in the "Resnatron," the useful emission which reaches the anode is dependent upon a space charge layer adjacent the cathode which is of sufficient "thinness" so as not materially to increase the transit 15 time of an electron in its trajectory between the cathode and the control grid. However, in order to achieve the best results with that type of tube, not only must the filament be capable of supplying 20 large quantities of electrons, but it must also preserve a uniform space relation with respect to the adjacent grid, even at the very high temperatures at which the filament operates.

25 Furthermore, it is highly important that the temperature at each point of the filament strip be as uniform as possible. Because of the necessity of providing relatively massive anchoring rings or supports for the multi-strip filament, the problem of "end cooling" is of much greater importance in ultra-high-frequency power tubes than it is in conventional tubes to be used at relatively 30 low frequencies. The filament supports for such ultra-high-frequency high power tubes must therefore perform three separate functions. They 35 must support the filament in the proper spatial relation to the grid; they must permit the filament strip to elongate when hot, to minimize "bowing"; and they must cause no substantial 40 "end cooling." I have found that these three objectives can be realized by appropriate design of the supports and by appropriate choice of materials, dimensions and shapes for the various components of the mount as a whole.

45 In the filament mount according to the invention, the filament consists of a series of linear parallel strips arranged in a circular array around a common center so as to cooperate with an adjacent grid. The support for such a mount there-

50 fore requires rigidity in the radial direction combined with a moderate amount of flexibility in the axial direction. I have found that these characteristics can be obtained by using thin-walled metal tubing supported in a rigid mounting ring at one end of the tubing, while the other end of the tubing is bent outward to form radial lugs which are spaced circumferentially from each other. Thus the elongation which occurs when the filament strips are heated, merely bends the lugs, but a radial displacement tends merely to 55 60

stretch the lugs without affecting the required rigidity of the filament support.

Such an arrangement is shown in generalized form in Fig. 1, comprising a thin-walled metal tube 1, for example of nickel, which at its lower end is welded or otherwise rigidly fastened to a copper ring 2. The upper end of tube 1 is bent at right angles to form the desired number of integral and radially extending lugs 3. Welded to the ends of lugs 3 are respective tabs 4 of a refractory metal such as tantalum. Vertically beneath the ring 2 and rigidly supported in spaced relation thereto is another copper ring 5 which has welded or otherwise fastened thereto another thin-walled metal tube 6 whose upper end is bent at right angles to form integral radial lugs 7 equal in number to, and vertically aligned with, the lugs 3. Welded to the lugs 7 are tabs 8 of refractory metal such as tantalum. Anchored at opposite ends to the respective tabs 4 and 8 are the various filament strips 8a of tungsten or other similar material which is conventionally used for electron-emitting cathodes in electron tubes. The filament strips are arranged to be heated by connecting the terminals of a suitable current supply respectively to rings 2 and 5. By proper design of the dimensions and materials for the various elements as described, no substantial "end cooling" of the filament strips takes place. Thus when the mount is properly designed, if the filament strips are removed and the two ends of the mount are joined together, the "hot" end of the mount would just reach filament operating temperature at the rated filament current. Consequently when the filament strips are assembled in the mount, they are suspended between supports which are at the same temperature as the filament, and no heat is conducted away from the filament ends. Therefore the cross-section of the mount should be carefully chosen so as to achieve the desired result. The temperature of the "hot" end of the filament is determined by a balance between the I^2R heat generated in the mount itself; by the heat lost through radiation from the mount itself; and by the heat conducted away from the "cool" end of the mount. This energy can be formulated in accordance with the following integro-differential equation:

$$J^2 \int_x^l \rho(T) dx = \sigma(T) \frac{dT}{dx} + F \int_x^l \gamma(T) dx \quad (1)$$

where:

J is the current density in the mount,

l is the length of the mount,

x is distance along the mount; $x=0$ at the cool end, and $x=l$ at the hot end.

$\rho(T)$ is the electrical resistivity of the mount material,

$\sigma(T)$ is the thermal conductivity of the mount material,

T is the temperature of the point x ,

F is the ratio of perimeter to area of the mount (shape factor), and

$\gamma(T)$ is the specific radiation coefficient of the mount material.

The formal solution of this equation is:

$$l \frac{1}{\sqrt{2}} \int_T^{T_1} \sigma(T) \left\{ \int_T^{T_1} [J^2 \rho(T) \sigma(T) - F \gamma(T) \sigma(T)] dt \right\}^{-\frac{1}{2}} dT \quad (2)$$

where T_1 is the temperature of the "hot" end and T that of the "cold" end.

When ρ , σ , and γ as functions of T are known experimentally, one can proceed to evaluate the

above integral either numerically or by using a polynomial approximation for the three functions. In this way by a series of trials one can find a combination of cross-section and length which gives the desired temperature drop.

While Fig. 1 shows the thin-walled tubular member 1 having one end bent over at right angles to form a series of separate radially extending lugs, this is not necessary. Thus the thin-walled tubular member 1 may be provided with a continuous right-angled flange, and the tabs 4 can be radially attached to this flange at appropriate circumferentially spaced points.

Referring to Figs. 2 to 4, there is shown one actual construction of mount which has been found to possess the desired characteristics. It comprises a lower ring 9 of copper or other metal of good heat conductivity. Fitted into a recess in the upper internal face of ring 9 is a thin-walled nickel tube 10, which may be welded to ring 9. The upper end of tube 10 is bent outwardly to form a right-angled flange 11. Welded to flange 11 so as to extend radially outward therefrom, are the equally spaced tantalum tabs 12. The outer end of each tab 12 may be in the form of a clip 13 to receive the right-angled end 14 of the corresponding filament strip 15 which may be welded to the tantalum tab.

The filament strips are arranged so that the main length 15 thereof extends parallel to the axis of ring 9. The upper end of each filament strip is likewise bent at right angles and is fastened or welded to a corresponding tantalum tab 16. The tabs 16 are welded to, and extend radially outward from, the flange lip 17 of a thin-walled nickel tube 18 similar to tube 10. The tube 18 is rigidly anchored or welded within a recess 19 in the lower face of the upper ring member 20 of copper or the like. It will be understood, that the tabs 16 are in vertical alignment with the corresponding tabs 12. If desired, the strips 15 throughout their vertical length may be provided with one or more vertically extending embossed recesses or corrugations 21 to increase their lateral rigidity. The rings 9 and 20 have respective flanges 22, 23, which extend outwardly along the horizontal portions of each filament strip to act as electron shields so that the electron emission from the filament strips is confined in general to a radial trajectory. The rings 9 and 20 are suitably fastened to respective rigid supports which may also be connected to the terminals of a suitable heating current supply. Thus, there is shown in Fig. 7, an enclosing evacuated vessel or housing 24. Extending through one end of this vessel is a tubular metal member 25 which fits over the ring 20 and can be fastened thereto by suitable screws 26. Likewise, there is fitted into the lower ring 9 a tubular metal member 27. The members 25 and 27 are connected to respective terminals of a suitable filament current supply source. The filament mount is surrounded by one or more suitable grids and an anode (not shown), so as to complete the electron circuit for the tube.

Referring to Figs. 5 and 6, there is shown a modification, wherein the filament strips instead

of being in the form of a tubular basket, are mounted in a radial planar array. In this embodiment there is provided a nickel ring 28 formed of thin-walled metal stock. Surrounding the

ring 28 and concentric therewith is another nickel ring 29 of thin-walled metal stock. Suitably attached, for example by welding, to the vertical rim of ring 28, are a series of tantalum tabs 30. Likewise welded or otherwise fastened to the vertical rim of ring 29 is a similar series of tantalum tabs 31, the tabs 30 and 31 being in radial alignment. The filament strips 32 are each in the form of a tungsten strip having the ends bent downwardly at right angles and welded or otherwise fastened to the ends of the corresponding tabs 30, 31. For the purpose of shielding the mount against back emission, there is welded to the ring 29 on the inner periphery thereof, a metal bracket 33 to which is fastened an annular metal disc 34 whose radial length is less than the length of the filament strips 32. The disc 34 is provided with a series of parallel upwardly extending channel members 35 which extend along, but in parallel spaced relation to, the edges of the associated filament strip. For the purpose of heating the filament strips, the rings 28 and 29 can be connected to suitable current supply terminals, it being understood that the rings 28 and 29 are supported in fixed coaxial relation in any well-known manner. Thus as shown in Fig. 8, the ring 28 is adapted to be fastened to a tubular member 36, and the ring 29 is adapted to be fastened to a similar outer tubular member 37, the members 36 and 37 being rigidly held in suitable concentric spaced relation. Associated with the filament is a suitable grid 38 which may have a series of radial openings each in alignment with a corresponding one of the filament strips 32. A suitable anode (not shown), and if desired, one or more additional grids may be used. The entire electrode assembly can then be enclosed within a suitable evacuated housing or envelope 39.

What is claimed is:

1. A multi-strand filament mount for electron tubes, comprising, a pair of coaxial annular filament anchoring members each in the form of thin-walled metal tubular stock, a plurality of radially discrete filament support tabs carried by the rim of one of said members, a corresponding plurality of radially discrete filament support tabs carried by the rim of the other of said members, the tabs on said members being in aligned pairs, and a plurality of filament strands each strand being anchored at its opposite ends to a corresponding aligned pair of said tabs, each of said thin-walled metal tubular members having a predetermined electrical resistance to develop a predetermined localized amount of heat adjacent the filament ends attached thereto in response to the filament current flowing therethrough to maintain the said filament ends at substantially the same temperature as the remaining portions of the filament.

2. A multi-strand filament mount according to claim 1, in which each of said tabs is an integral extension of the rim of the corresponding one of said members each of said strands has a main portion extending parallel to the common axis of said coaxial members, and a pair of laterally extending portions which are respectively anchored to said annular members around the periphery thereof.

3. A multi-strand filament mount according to claim 1, in which each of said strands has a main portion extending radially outward from the common center of said coaxial members, and a pair of laterally extending portions which are an-

chored respectively to said coaxial members around the periphery thereof.

4. A multi-strand filament mount for electron tubes, comprising, a pair of coaxial annular filament anchoring members each in the form of thin-walled metal tubular stock having its rim bent at substantially right angles, a ring of highly conductive metal for each member and to which it is rigidly fastened while permitting said rim to flex with respect to the ring, a plurality of radially discrete filament support tabs carried by the rim of one of said members, a corresponding plurality of radially discrete filament support tabs carried by the rim of the other of said members, the tabs on said members being arranged in aligned pairs, and a plurality of filament strands each anchored at its opposite ends to a corresponding aligned pair of tabs, each of said thin-walled metal tubular members having a predetermined electrical resistance to develop a predetermined localized amount of heat adjacent the filament ends attached thereto in response to the filament current flowing therethrough to maintain the said filament ends at substantially the same temperature as the remaining portions of the filament.

5. A filament mount according to claim 4, in which each of said rings is rigid in a radial direction.

30. 6. A multi-strand filament mount for electron tubes, comprising, a pair of spaced coaxial annular filament anchoring members each of thin-walled tubular metal stock, a plurality of radially discrete filament anchoring lugs radially extending from the rim of one of said members, a corresponding plurality of radially discrete filament anchoring lugs radially extending from the rim of the other of said members, the lugs being arranged in aligned pairs, a filament clip attached to each lug, and a filament strand fastened at its opposite ends to a corresponding pair of said clips.

7. A multi-strand filament mount for electron tubes, comprising, a pair of spaced coaxial annular filament anchoring members each of thin-walled tubular metal stock, each member having an integral flange, a plurality of radially discrete filament support tabs fastened to the flange on one member, a corresponding plurality of radially discrete filament support tabs fastened to the flange on the other member, and a plurality of filament strands each strand having its opposite ends connected respectively to a tab on one flange and the corresponding tab on the other flange, each of said thin-walled metal tubular members having a predetermined electrical resistance to develop a predetermined localized amount of heat adjacent the filament ends attached thereto in response to the filament current flowing therethrough to maintain the said filament ends at substantially the same temperature as the remaining portions of the filament.

8. A multi-strand filament mount, comprising, a pair of axially spaced annular members of thin-walled metal stock, a ring of highly conductive metal to which one annular member is fastened, another ring of highly conductive metal to which the other annular member is fastened, and a plurality of filament strands bridged across the rims of said annular members to form a basket-like structure, each of said thin-walled annular members having a predetermined electrical resistance to develop a predetermined localized amount of heat adjacent the filament ends attached thereto in response to the filament cur-

rent flowing therethrough to maintain the said filament ends at substantially the same temperature as the remaining portions of the filament, each of said rims having attached thereto a series of circumferentially spaced radially discrete anchoring tabs to which the respective ends of said filament strands are connected.

9. A multi-strand filament mount, comprising, a pair of radially spaced annular members of thin-walled metal stock, a radially rigid metal ring to which one of said members is fastened, another radially rigid metal ring to which the other of said members is fastened, each of said annular members having a flange extending parallel to their common axis, and a plurality of filament strips bridged across said flanges and disposed in radially extending array around said common axis, said thin-walled annular members having a predetermined electrical resistance to develop a predetermined localized amount of heat adjacent the filament ends attached thereto in response to the filament current flowing therethrough to maintain the said filament ends at substantially the same temperature as the remaining portions of the filament, each of said flanges having attached thereto a series of circumferentially spaced radially discrete anchoring tabs to which the respective ends of the said filament strips are connected.

10. A multi-strand filament mount for electron tubes, comprising in combination a pair of annular metal blocks, a tubular member of thin-walled metal stock fastened to one of said blocks, another tubular member of thin-walled metal stock fastened to the other block, each of said members having a cross-sectional thickness which is small in comparison with the cross-sectional thickness of the associated block and having an integral flange of small cross-sectional thickness extending radially therefrom, and a plurality of filament strips each being anchored at its opposite ends to a respective one of said flanges through the intermediary of respective radially discrete lugs attached to said flanges, and each of said thin-walled metal tubular members having a predetermined electrical resistance which is low in comparison with the electrical resistance of the associated block for developing a predetermined localized amount of heat adjacent the filament ends attached to the blocks in response to filament current flowing therethrough and thereby maintaining said filament ends at substantially the same temperature as the remaining portions of the filament.

11. A multi-strand filament mount for electron tubes, comprising in combination a pair of annular metal blocks of high conductivity, a tubular metal member of thin-walled stock fastened to

one of said blocks, another tubular metal member of thin-walled stock fastened to the other block, each of said members having a cross-sectional thickness which is small in comparison with the cross-sectional thickness of the associated block, each member having an integral flange extending radially outward therefrom, a plurality of discrete filament support tabs in spaced relation around each of said flanges, and a plurality of filament strips each having its opposite ends anchored to a corresponding pair of said tabs and each of said thin-walled tubular members and flanges having a predetermined electrical resistance which is high in comparison with the electrical resistance of the associated block for developing a predetermined localized amount of heat adjacent the filament ends attached thereto in response to the filament current flow to thereby maintain the said filament ends at substantially the same temperature as the remaining portions of the filament.

12. A multi-strand filament mount according to claim 11 in which each of said metal blocks is of copper and said tubular members are of nickel, said tabs being of tantalum and said filament strips being of tungsten.

13. A filament mount for high power radio tubes, comprising in combination a pair of spaced metal bodies of good heat conductivity and low electric resistance, a plurality of filament strands supported at opposite ends from said bodies, and means interposed between each filament end and its point of attachment to the associated metal body, the last-mentioned means being of a material different from the material of said bodies and having a much higher electrical resistance for developing a predetermined localized amount of heat adjacent the said points of attachment of the filament strands by reason of the filament current flowing therethrough which localized heat maintains the filament ends at substantially the same temperature as the remainder of the filament.
